UNITED STATES PATENT OFFICE.

RICHARD N. EDWARDS, OF WILLIAMSVILLE, MISSOURI, ASSIGNOR OF ONE-HALF TO J. H. HARTY, OF MINGO, MISSOURI.

HAND-BRAKE FOR CARS.

SPECIFICATION forming part of Letters Patent No. 715,250, dated December 9, 1902.

Application filed January 27, 1902. Serial No. 91,425. (No model.)

To all whom it may concern:

Be it known that I, RICHARD N. EDWARDS, a citizen of the United States, residing at Williamsville, in the county of Wayne and State of Missouri, have invented a new and useful Hand-Brake for Cars, of which the following is a specification.

This invention relates generally to car-brakes; and the object of the invention is to provide a brake-operating mechanism capable of being operated by hand either from the top of the car or the side thereof.

With these objects in view the invention consists in the novel features of construction and combination, all of which will be fully described hereinafter and pointed out in the claims.

In the drawings forming a part of this specification, Figure 1 is a perspective view showing the practical application of my invention. Fig. 2 is an enlarged detailed perspective view. Fig. 3 is a detail view showing the reversible pawl. Fig. 4 is a vertical sectional view showing the relative arrangement of the combined pawls and gears. Fig. 5 is a detail in elevation showing the weight for holding the locking-pawl in position. Fig. 6 is a detail perspective view showing the several parts of said pawl and weight detached, and Fig. 7 is a detail perspective view of the journal-bracket.

In carrying out my invention I employ a combined journal-bracket A, having the vertical bearing A' and the horizontal bearing A², said bearings being connected by means of an angular arm A³, from which extend the brace-rods A⁴, by means of which the bracket is attached to the bottom timbers of the car. A vertical shaft B is journaled in the vertical bearing A', the upper end of said shaft being journaled in a bracket C, the construction of which will be described hereinafter. A beveled gear D is mounted upon the shaft B and rests upon the bearing A', said beveled gear having an integral ratchet-disk D' arranged beneath the same, said disk having the peripheral ratchet-teeth D² and the upper or crown ratchet-teeth D³. A horizontal shaft E is journaled in the horizontal bearing A²

and carries a beveled gear F upon its inner end, the teeth of said gear F meshing with the beveled gear D. The ratchet-wheel F' is formed integral with the gear F, and a hand-lever G is mounted upon the reduced end of the horizontal bearing A², said lever carrying a double reversible pawl H, which is adapted to engage the ratchet-wheel F', said pawl having the points H' and H² and the enlarged or weighted portion H³, the pivot H⁴ being arranged in advance of both points H' and H², so that no matter which side of the pivot the weighted portion rests upon either the point H' or H² will engage the ratchet-wheel. A pawl I is pivoted to a bracket K and is adapted to engage crown ratchet-teeth D³ of the disk or wheel D', said pawl having a weighted portion I', which normally holds it out of engagement with the said teeth. A weight K' is pivoted between the ears K² of the bracket K and is adapted to rest upon the end of the pawl I for the purpose of holding the same in engagement with the ratchet-teeth D³. The bracket C, which is fastened to the end of the car, comprises a central portion C', in which the upper end of the shaft B is journaled, and the transversely-slotted portion C², in which the upper end of the lever G works. The lower end of the shaft B is connected to the brake mechanism by means of the chain L.

M indicates the hand-wheel, arranged upon the upper end of the shaft N, said shaft being journaled in brackets upon the end of the car and provided at its lower end with a clutch-joint N', by means of which connection is had with the upper end of the shaft B.

By means of the device herein shown and described a brake can be applied either by turning the hand-wheel M at the top of the car or by working the lever G from the side of the car. It will also be understood that the operation of the brake mechanism by the hand-lever will not interfere with the operation of the hand-wheel at the top of the car, nor will the operation of the brake mechanism by means of the hand-wheel at the top of the car interfere with or operate the hand-lever mechanism.

Having thus fully described my invention, what I claim as new, and desire to secure by Letters Patent of the United States, is—

1. A brake-operating means, comprising a brake-shaft having a combined gear and ratchet wheel mounted thereon, the upper end of said shaft being operatively connected to a hand-wheel shaft, a gear-wheel journaled transversely to the first-mentioned gear and meshing therewith, said last-mentioned gear having a ratchet-wheel integral therewith, and a lever carrying a pawl adapted to engage the said ratchet-wheel, substantially as described.
- 15 2. A brake-operating means comprising a brake-shaft provided with means at its upper end for connection with a hand-wheel, a combined gear and ratchet wheel mounted adjacent to the lower end of the brake-shaft, a pawl pivoted adjacent to the said combination gear and ratchet wheel, a weight adapted to bear upon the said pawl, a combination gear and ratchet wheel arranged transversely to the first-mentioned gear and ratchet wheel,

the gear-teeth being adapted to mesh, an operating-lever and pawl connected thereto, substantially as shown and described.

3. In a device of the kind described, the combination with the brake-shaft, of the combination gear and ratchet wheel arranged thereon, a pawl pivoted adjacent to the said combination gear and ratchet and provided with a weight at its lower end to normally hold the upper end out of engagement, and a pivoted weight adapted to bear upon the free end of the pawl, substantially as shown and described.

4. In a brake-operating mechanism, the combination with the horizontal shaft having a combined gear and ratchet arranged thereon, an operating-lever and a double reversible pawl pivoted to the lever and adapted to engage the ratchet, substantially as shown and described.

R. N. EDWARDS.
